J. LYALL.

CARPET.

No. 17,779.

Patented Oct. 11, 1887

UNITED STATES PATENT OFFICE.

JAMES LYALL, OF NEW YORK, N. Y.

DESIGN FOR A CARPET.

SPECIFICATION forming part of Design No. 17,779, dated October 11, 1887.

Application filed September 10, 1887. Serial No. 249,395. Term of patent 14 years.

To all whom it may concern:

Be it known that I, JAMES LYALL, of the city and State of New York, have invented a Design for a Carpet, of which the following is

5 a description.

The design of this carpet is represented in the accompanying photograph.

There are stripes *a b* running along the carpet having contrasting colors, and the stripes are 10 subdivided so as to form blocks of patterns. The blocks 1 in the stripes *a* have ranges of longitudinal lines lapping one beyond the other, so as to form a series of diagonal patterns. The blocks 2 have ranges of transverse lines lap- 15 ping one beyond the other, so as to form a series of diagonal patterns that contrast in color with the diagonal patterns in the blocks 1. The blocks 3 in the stripes *b* have ranges of longitudinal lines lapping one beyond the other to 20 form zigzag diagonal patterns, and the blocks 4 have ranges of transverse lines lapping one

beyond the other to form zigzag diagonal patterns that contrast with the patterns in the blocks 3, and the stripes *b* are further subdivided by narrow longitudinal stripes of contrasting color.

I claim—

The design of the carpet-pattern represented, consisting in the design of the longitudinal stripes subdivided into blocks with longitudinal lines lapping past each other in one set of blocks and transverse lines lapping past each other in the alternate blocks, and forming in the stripes *a* diagonal patterns and in the stripes *b* zigzag patterns, substantially as represented. 35

Signed by me this 6th day of September, A. D. 1887.

JAMES LYALL.
